UNITED STATES PATENT OFFICE.

JOSEPH A. STUTSMAN, OF MELROSE, MASSACHUSETTS.

AMMONIA-CONDENSING APPARATUS.

1,148,725.

Specification of Letters Patent. Patented Aug. 3, 1915.

Application filed February 6, 1913. Serial No. 746,441.

To all whom it may concern:

Be it known that I, JOSEPH A. STUTSMAN, a citizen of the United States, residing at Melrose, in the county of Middlesex, State of Massachusetts, have invented a certain new and useful Improvement in Ammonia-Condensing Apparatus, of which the following is a specification, reference being had thereto in the accompanying drawings.

10 My invention relates to condensing apparatus for condensing and liquefying gas preparatory to employing the same in apparatus designed to utilize gas in a liquid form, as for example in refrigerating machinery.

15 In the type of condensing apparatus to which my invention more particularly relates, the liquefaction of the gas is effected by introducing gas which has previously been more or less compressed, into a receptacle commonly made up in the form of a series of coils or pipes of a length calculated to give relatively large superficial area as compared with its capacity, which receptacle is in part filled with a liquid, which is preferably a body of previously liquefied and cooled gas of the same nature as that in process of liquefaction. The compressed gas which is introduced into the said receptacle is discharged into the liquefied gas therein contained, and by intimately intermingling with the same, facilitates the liquefaction of the gas in a manner well understood by those conversant in the art. Water or other cooling agents are preferably caused to flow from the exterior of said pipes containing the intermingled gas and liquefied gas for the purpose of cooling the same.

20 My invention more especially consists in a novel construction of apparatus for effecting the condensation of the compressed gas under the specially favorable conditions made possible by such arrangement and

25 which enables me to secure a high efficiency in the amount of gas condensable for a given area of surface of the condensing apparatus. Such novel construction is more particularly characterized by an improved form of apparatus designed to effect a more thorough and intimate intermingling with the previously liquefied gas, of the compressed gas introduced into the receptacle; and by the arrangement of the pipes or coils forming 30 the receptacle containing the intermingled compressed gas and liquefied gas as to pro-

duce a circulation of the said mixture therein in such manner as to secure a higher condensing efficiency of the apparatus.

In such drawings Figure 1 is a side view 60 of an improved ammonia condensing apparatus embodying my invention. Fig. 2 is a view of the same, taken on the plane $\alpha-\alpha$. Fig. 3 is a partly sectional detail view, on an enlarged scale, showing the construction 65 of my "interchanger", so called. Fig. 4 is an end view of said interchanger. Fig. 5 is a partly sectional view of the special fitting 6.

The condensing apparatus shown in Figs. 70 1 and 2 consists largely of pipes which are combined and interconnected by suitable fittings, valves and other apparatus as and in the manner hereinafter described.

The ammonia gas, is delivered from a 75 compressor, not shown in the drawings, in a state of compression through the gas inlet pipe or conduit 1, leading to the side outlet of a T 2. From the end outlets of the T 2 extend in either direction pipes 3, 3, preferably having a combined area approaching that of the pipe, 1. The free ends of the pipes 3, 3, are connected through return bends 4, 4, to the pipes 5, 5, of which the ends meet above the T 2. Said meeting ends 80 of the pipes 5, 5, are secured into a special fitting 6, which, as shown in detail in Fig. 5, substantially embodies two longitudinally passaged portions 7 and 8, intercommunicating through the passaged connection 9, 90 the former passaged portion 7 being adapted at each end to engage the said pipes 5, 5, and the portion 8, the pipes 10, 10, herein-after mentioned. From the passaged portion 8 of the said fitting 6, pipes 10 lead in 95 opposite directions to the return bends 11, 11, which are in turn connected through the pipes 12, 12, to apertures provided in the lower portion 13 of the interchanger, as is more clearly shown in detail in Fig. 3. 100

Referring to said Figs. 3 and 4, the interchanger embodies a lower or gas supply portion, 13 somewhat resembling a T, having main outlets to which are connected the pipes 12, 12, and having its side outlet 105 closed by a preferably faced flange 14. The top or liquid intake portion 15 of said interchanger is substantially identical with the gas supply or lower portion 13, and comprises a portion resembling a T having 110 main outlets to which are connected the pipes 24, 24, hereinafter to be mentioned,

but having its side outlet closed by a flange 16, preferably faced and jointly held against the faced flange 14 of the lower portion 13 of the interchanger as by the bolts 17, a gasket 18 being preferably interposed between said faced flanges to insure a leakage-proof joint. At one side of said upper portion 15 is provided a lateral inlet 19 for the purpose as hereinafter described. Passing through both said flanges 14 and 16, and engaging preferably the lower flange 14 with a leakage proof joint, as by a pipe threaded joint therewith, is a pipe 21 forming a part of and constituting an inlet to the interchanger nozzle, which pipe 21 is of a suitable size to permit the free flow therethrough of the gas to be discharged from the nozzle. The interchanger nozzle may be conveniently made up by entering the free end of the inlet pipe 21, within the side outlet of a T 22, from the end outlets of which T 22 extend in opposite direction short outlet pipes or discharge outlets 23, 23. If desired the inlet pipe 21, the T 22, and the discharge outlets, all forming the interchanger nozzle, may be constructed in one integral casting. The length of the inlet pipe 21, is preferably such that said discharge outlets 23, 23, are substantially axially located within the pipes 24, 24, leading from the upper or liquid-intake portion of the interchanger, and the said outlets are preferably of sufficient length to enter for a short distance within said pipes 24, 24. From said main outlets of the upper portion 15 of the interchanger, lead in opposite directions the pipes 24, 24, to the return bends 25, 25, whence extends a series of pipes connected at their inner ends by fittings like that indicated by the numeral 6 and hereinbefore described, and at their outer ends by return bends, the number of which pipes is largely dependent upon the particular area of the condenser surface which it is desired to secure. Said pipes ultimately unite at the T 26, from which a preferably reduced outlet 27 leads to valve 28 discharging by pipe 29 into the inlet of a three-way L 30. One outlet of said L is piped into the said lateral outlet 19 of the upper portion 15 of the interchanger. The other outlet of such L is connected by the pipe 31 through the valve 32 to the liquid header 33.

55 The operation of my improved condensing apparatus is as follows: The compressed and hot ammonia gas enters the condensing apparatus from the compressor, not shown in the drawings through the pipe 1. Dividing at the T 2 the compressed hot gas passes outward to the return bends 4, unites again at the fitting 6, and thereafter again divides and passes outwardly through the return bends 11, 11, and finally returning and reuniting in the lower portion 13 of

the interchanger. In the process of its passage through the piping or coil to this point the heat incident to compressing the gas has been to a large degree dissipated and preferably water or other cooling agents are allowed to trickle over said pipes by means not shown in the drawings but familiar to those conversant in the art to facilitate such cooling. The portion of the condensing apparatus to this point is commonly referred to as the pre-cooler, or the pre-cooling portion of the condensing apparatus.

The piping forming the upper portion of the condensing apparatus and leading from and located above the interchanger is termed the gas liquefying condensing portion or liquefying coil of the condensing apparatus, or the "condenser" as the same is hereinafter referred to for brevity. Said condenser is filled, under a pressure somewhat less than that existing in the pre-cooler with liquefied gas which is more or less permeated with compressed gas which has been mingled therewith and is a process of liquefaction as hereinafter described, the unliquefied gas being present in largest quantity in the coils of the condenser immediately adjacent the interchanger but being more or less completely liquefied by the time the mixture completes its circulation through the condenser and arrives at the T 26. The said liquefied gas is admitted into the gas liquefying coil through the inlet 19 leading into the upper portion 15 of the interchanger, and into the liquid so introduced and standing more directly in the pipes adjacent the said interchanger on either side, is discharged from the discharge outlets 23, 23, the compressed gas which has traversed the pre-cooler and has reached the lower portion of the interchanger; the velocity of such discharge depending on the difference of the pressures existing in pre-cooler and gas liquefying coil. Such gas passing from the lower portion of the interchanger through the pipe 21 into the interchanger nozzles, is discharged through the discharge outlets 23, 23, into the center of the fluid into the liquid gas standing in said pipes 24, 24, in opposite directions. Such discharge produces an intimate intermingling of the compressed and cooled gas with the previously liquefied gas contained therein and at the same time the velocity of the discharge of the compressed gas from each discharge outlet 23, 23, into the pipe 24, causes a movement of said liquid gas therein, which results in drawing into the same from the liquid inlet position of the interchanger the liquid gas entering the same from the liquid inlet 19. In this manner the said liquid gas is caused to divide in separate streams entering the pipes 24, 24, extending in opposite directions from the interchanger, and flowing in opposite

directions therein. The compressed gas discharged from the discharge outlets 23, 23, into such oppositely flowing streams mingle therewith and tend to become condensed 5 therein. Such streams of intermingled gas and liquid traverse the pipes 24, 24, to the return bends 25, 25, whence the mixture thereafter circulates sinuously alternately inwardly and again outwardly through the 10 remaining pipes included in the condenser until the mixture of the liquid gas and the gas newly condensed therein reaches the valve 28, by which time all the compressed gas has become liquid. The major part of 15 such liquid after passing said valve 28 again reenters the liquid intake portion of the interchanger through the piping leading to the lateral inlet 19 and again commingling with a fresh supply of compressed gas discharged from the nozzles 23, 23, repeats its 20 circulation through the gas liquefying coil. By means of the valve 28 the rate of circulation of the liquid through the gas liquefying coil may be regulated and adjusted 25 as desired. Any accession to the quantity of liquid gas contained in the condenser which may accumulate by reason of the condensation of gas in excess of the capacity of the condenser, may discharge through 30 the pipe 31 and valve 32 into the liquid-header 33.

I am aware that condensing apparatus has been hitherto constructed in which the compressed gas after passing through a pre-cooler has been discharged directly into gas 35 which has been previously liquefied. In such apparatus, however, so far as I am advised, such discharge has been arranged to take place through a single discharge outlet, 40 which outlet has been located at one end of a single continuous pipe in which such mixture of compressed and liquefied gas is designed to circulate, and within which the liquefaction of such compressed gas is completed. Furthermore, so far as I am advised, the discharge of the gas into the 45 receptacle or coil has been arranged to take place through a single discharge outlet or nozzle which outlet has been located at one end of a single continuous pipe, in which the mixture of the compressed gas and liquefied gas is designed to circulate and within which the liquefaction of such compressed gas is completed. In my apparatus, 50 however, the discharge of compressed gas into the liquefied gas takes place at a point substantially central in the condenser coils and through a plurality of discharge outlets. In consequence the intermingling of 55 compressed gas and liquid gas is more intimately accomplished in my apparatus than in those of the prior type. Furthermore assuming equal condenser areas and coil sizes, and equal quantities of compressed 60 gas and liquefied gas, the rate of circula-

tion through the condenser coils is slower in my condenser than in the prior condensers. The above advantages result in an improved gas condensing and liquefying efficiency and a consequent economy of operation for my 70 condenser as compared with those previously constructed.

The number and size of the pipes employed to make up the pre-cooler and condenser embodied in my condensing apparatus may be varied to suit the requirements of the plant to which the same is applied. Furthermore it will be evident that the position of the interchanger with respect to the coils of pipe embodied in the condensing 80 apparatus may be changed in order to vary the proportion of the pre-cooling surface to that of the condenser surface in the condensing apparatus. For instance the interchanger may be substituted for the fitting 85 6, in which case the pipe 29 is correspondingly lengthened.

Having described my invention what I claim and desire to secure by Letters Patent is:—

1. In gas condensing apparatus, a gas liquefying coil embodying a liquid intake and having diverging branches extending in opposite directions from said liquid intake, a conduit for conducting gas under 90 pressure, a gas inlet connected with said conduit and embodying a plurality of discharge nozzles located within said liquid intake and arranged to discharge gas from the conduit into said diverging branches 95 adjacent said liquid intake and thereby to create a circulation of liquid in said branches from said liquid intake to the discharging ends of such branches, means for reconducting a part of the liquid gas 100 discharged at the discharging ends of said diverging branches back to said liquid intake, and for conducting the remainder of such gas to a storage receptacle.

2. In gas condensing apparatus, a gas liquefying coil embodying a liquid intake and having two branches symmetrically disposed on opposite sides of said liquid intake, a conduit for conducting gas under 110 pressure, a gas inlet piped to said conduit and embodying nozzles located within said intake, each of said nozzles being arranged to introduce gas discharged therefrom into one of said branches and to create a circulation of liquid therein from said liquid 115 intake to the outlet end of the branch means for returning a part of the liquefied gas discharged at the outlet end of said branches back to said liquid intake and means for conducting the remainder of such liquefied 120 gas to a storage receptacle.

3. In gas condensing apparatus, a gas liquefying coil embodying a liquid intake and having a plurality of branches symmetrically disposed on opposite sides of 125

said liquid intake, a conduit for conducting gas under pressure, a gas inlet piped to said conduit and embodying a plurality of nozzles located within said intake, each nozzle being arranged to introduce gas discharged therefrom into one of said branches and to create a circulation of liquid therein from said liquid intake to the outlet end of the branch, means intermediate the conduit and the gas inlet for precooling the gas, means for returning a part of the liquefied gas

discharged at the outlet end of the said branches back to the said liquid intake, and means for conducting the remainder of such liquefied gas to the storage receptacle. 15

In testimony whereof I affix my signature in presence of two witnesses.

JOSEPH A. STUTSMAN.
